UNITED STATES PATENT OFFICE.

ROBERT W. WEATHERMAN, OF SELMORE, MISSOURI, ASSIGNOR OF ONE-HALF TO FLOYD HARTLEY, OF SELMORE, MISSOURI.

PUNCH AND BOLT-CUTTER.

975,006.

Specification of Letters Patent.

Patented Nov. 8, 1910.

Application filed December 23, 1909. Serial No. 534,748.

To all whom it may concern:

Be it known that I, ROBERT W. WEATHERMAN, a citizen of the United States of America, residing at Selmore, in the county of Christian and State of Missouri, have invented a new and useful Punch and Bolt-Cutter, of which the following is a specification.

This invention relates to hand tools and 10 has special reference to a combined punch and bolt cutter.

The principal object of the invention is to improve and simplify the construction of devices of this character.

15 Another object of the invention is to provide a device of this character wherein the stem of the punch will constitute the actuating means for a movable cutter blade.

With the above and other objects in view 20 the invention consists in general of certain novel details of construction and combinations of parts hereinafter fully described, illustrated in the accompanying drawings and specifically set forth in the claim.

25 In the accompanying drawings, like characters of reference indicate like parts in the several views, and:—Figure 1 is a side elevation from one side of the machine with the blades closed. Fig. 2 is a side elevation 30 from the other side of the machine with the blades and punch open. Fig. 3 is a plan view of the operating end of the device. Fig. 4 is a view similar to Fig. 2 but showing the blades and punch closed.

35 The body of the invention comprises a shank 10 which has on one end a handle 11 and on the opposite end is provided with an angular extension 12 wherein is formed an opening 13 adapted to receive the end of a

40 punch. Extending parallel to the member 12 and in spaced relation thereto there is provided an arm 14 and to this arm and the body 10 is secured a fixed blade 15. The arm 14 is so arranged that the blade 15 may 45 lie flat against said arm and the side of the member 10. Secured to the blade 15 by means of one of the bolts 16 is a plate 17 which extends toward the handle 11 and the end adjacent the handle has a pivot bolt 18 50 passing therethrough and also through the body 10, the bolt being held in position by means of a suitable nut. On this pivot bolt is mounted a swinging blade 19 which is so arranged that the edge thereof may be

brought into contact with the edge of the 55 blade 15 as can clearly be seen by reference to the drawings. This blade 19 is provided with a slot 20 extending in a direction substantially longitudinally of said blade. Extending in a direction opposite the arm 14 60 and preferably integral with the body 10 is a second arm 21 whereto is pivoted one end of a lever 22 provided with a handle 23. Pivoted to the member 10 is a lever 24 which is provided at one end with a slot 25. 65 Through this slot 25 and the lever 22 extends a bolt 26 which is slidable in the slot.

The arm 14 is provided with a suitable opening for the reception of the shank 27 of a punch holder, the shank and opening being 70 of such dimensions that the shank is freely slidable in said opening. Furthermore, this opening is concentric with the opening 13 so that a punch 28 held in the holder may be made to pass into the opening 13 by proper 75 movement of said holder. The end of the shank 27 opposite the punch 28 is flattened to form a head 29 and through this head and the slot 20 passes a bolt 30, the bolt being freely slidable in said slot. The head 29 is, 80 furthermore, connected to the lever 24 by means of a bolt 31.

The body 10 is preferably made with the portion between the arm 21 and the handle 11 of rectangular cross section and of the 85 same dimensions throughout. On this portion of the body is slidably mounted a stop member 32 having a suitable opening where-through the body passes and being provided with a set screw 33 so that the stop member 90 can be positioned at any desired point along the body 10.

In the operation of the device the handles 11 and 23 are grasped and moved to the positions shown in Fig. 2. A sheet of metal is 95 then inserted between the punch 28 and the member 12 or a sheet or bolt may be placed between the blades 15 and 19. The handles 11 and 23 are then forcibly brought together and the metal in either position will be severed. It is to be noted that the stop member 32 is so positioned that the handles 11 and 100 23 cannot be brought together sufficiently close to injure the edges of the blades 15 and 19. It will be seen also that the construction herein set forth provides for the shank 27 having the double function of a punch holder and of means to connect the lever 24 105

with the blade 19. In like manner the arm 14 constitutes a support for the blade 15 and a guide for the shank 27.

There has thus been provided a simple 5 and efficient device of the kind described and for the purpose specified.

Having thus described the invention, what is claimed as new, is:—

1. In a tool of the class described, a body 10 comprising a handled bar having an arm projecting laterally therefrom, said arm having an opening formed therethrough, a blade fixed to said arm and bar, a second blade pivoted to the bar to swing to and from the 15 fixed blade and provided with a longitudinally extending slot, a lever pivoted intermediate its ends to said bar and provided with a slot at one end, a member having a shank extending through the opening in 20 said arm and slidable therein, a bolt passing through said member and the slot in the movable blade, a second bolt passing through said member and the end of the lever opposite the slot therein, a second arm projecting 25 from said bar in the opposite direction to the first arm, a second lever fulcrumed to said second arm and provided with a handle; and a third bolt passing through said second lever and the slot in the first lever.

2. In a tool of the class described, a body 30 comprising a handled bar having an arm projecting laterally therefrom, said arm having an opening formed therethrough, a blade fixed to said arm and bar, a second blade pivoted to the bar to swing to and from the 35 fixed blade and provided with a longitudinally extending slot, a lever pivoted intermediate its ends to said bar and provided with a slot at one end, a member having a shank extending through the opening in said 40 arm and slidable therein, a bolt passing through said member and the slot in the movable blade, a second bolt passing through said member and the end of the lever opposite the slot therein, a second arm projecting 45 from said bar in the opposite direction to the first arm, a second lever fulcrumed to said second arm and provided with a handle, a third bolt passing through said second lever and the slot in the first lever, a stop 50 for the second lever slidable on said bar, and means to hold said stop in adjusted position on the bar.

ROBERT W. WEATHERMAN.
